UNITED STATES PATENT OFFICE.

LESTER KIRSCHBRAUN, OF CHICAGO, ILLINOIS.

PROCESS OF MAKING MULTIPLY WATERPROOF SHEETS.

Application filed August 16, 1922. Serial No. 582,303.

The present invention is more particularly directed to the manufacture of a multiply sheet in which a relatively thin film of waterproofing material is interposed between certain plies.

In carrying out the present invention I make an emulsion miscible in water which may consist of water, an emulsifying agent, as for example colloidal clay or Bentonite, and pitch or bitumen, as for example, solid or semi-solid asphalt. The emulsion may be formed as a continuous operation, for example, in the manner described in my prior Patent No. 1,417,835.

15 This emulsion when formed may be, if desired, sufficiently thinned with water so that it will readily flow and can be applied as a thin film. By means of the present invention, the waterproofing material is so applied as to avoid any waste. Also the process is so carried out that the bituminous or pitchy emulsion does not come in contact with any of the screens or blankets, or any other operating parts of the machine. This 20 permits of the use of an emulsion which is not nearly as non-adhesive as is the case where the emulsion is mixed with the paper stock and formed on the moulds and thereby permits of a much wider range in character 25 of emulsions suitable for use in this connection. In order to more clearly understand the invention I show the accompanying drawing in which the single figure is a more or less diagrammatic view of an apparatus suitable for carrying out the process.

Referring to the drawings 1, 2, 3 and 4 designate vats in which are mounted the usual cylinder moulds 5, 6, 7 and 8 on which respective plies are built up. The vats are 40 provided with the usual couch rolls 9 and blanket 10. Between any of the vats may be interposed an emulsion distributing vat. In the present instance the vat is shown only as between the vats 2 and 3, but it may also be interposed by vats 1 and 2 and tanks 3 and 4 if desired. Also there may be 6 and 8 cylinder moulds with distributing vats between each pair of moulds if desired.

In the present instance I only show one 45 distributing vat, 11 in which is mounted applying mould or roll 12, and above which is mounted a depressible yieldably mounted presser roll 13, which acts as a couch roll. This roll 13 is so mounted as to in effect act as a couch roll and prevent the picking off 55 of the film from the blanket by the dis-

tributing mould. Likewise it adjusts the degree of contact between the wet film of paper and the distributing mould in such a manner that the freshly formed fibrous film 60 on the blanket is not disturbed or mutilated. The roll 12 may be either a solid metal or wooden roll, or preferably it may be covered with a wire mesh or suitable fabric for picking up the desired quantity of emulsion. 65

In carrying out the process in the manner particularly illustrated in the drawings, the fibrous plies are formed respectively on the rolls 5, 6, 7 and 8 and as the previously formed plies pass between the rolls 12 and 70 13, a relatively thin film of the emulsion is applied to the under-face of the lower ply and as the plies pass between the rolls 7 and 9 a fibre ply is built up on the roll 7. The upper face of this ply is of course thus 75 coated with the emulsion film. The three plies then pass between the rolls 9 and 8 and the last ply is built up. The various plies carried on the blanket may then pass to the usual presser and drying rolls of a 80 multicylinder machine. The water will accordingly be removed from the emulsion which will be broken and the asphalt film coalesce and form a continuous waterproof medium between the plies in question. 85

If desired, more or less fibrous stock may be mixed with the emulsion before it is placed in the distributing tank 11, which acts as a reinforcement for the bituminous film. 90

I claim as my invention:

1. A process for making a waterproofed multiply sheet which consists in uniting a plurality of wet fibrous plies and simultaneously with the formation of the plies interposing by a rolling action a continuous waterproofing film between a plurality of plies, said waterproofing film being in the form of an emulsion miscible in water at the time it is applied. 95

2. A process for making a waterproofed multiply sheet which consists in uniting a plurality of wet fibrous plies and simultaneously with the formation of the plies interposing by a rolling action a continuous waterproofing film between a plurality of plies, said waterproofing film being in the form of an emulsion miscible in water at the time it is applied, comprising essentially a bituminous like binder and an emulsifying agent. 105

3. A method of producing a waterproofed

sheet which comprises forming a wet fibrous web, in bringing said wet fibrous web into contact with a moving surface carrying an aqueous film of waterproofing material in the form of an emulsion miscible in water, and transferring said emulsion as a preformed continuous film to said wet web.

4. A method of producing a waterproofed sheet which comprises forming a wet fibrous web, in bringing said wet fibrous web into contact with a moving surface carrying an aqueous film of waterproofing material in the form of an emulsion miscible in water, transferring said emulsion as a preformed continuous film to said wet web, and in then uniting a second wet fibrous web thereto whereby said continuous film is interposed between the webs.

5. A method of producing a waterproofed sheet which comprises forming a wet fibrous web, in transferring to the underside of the wet fibrous web an aqueous bituminous emulsion, as a preformed film.

6. A process of producing a waterproofed sheet which comprises forming a wet fibrous web, in transferring to the underside of said wet fibrous web an aqueous bituminous film of waterproofing material by a rolling contacting action, and in thereafter uniting a second fibrous web with the underside of said first mentioned web whereby said film is interposed between the webs.

7. A process for making a waterproofed multiply sheet which consists in uniting a plurality of wet fibrous plies and simultaneously with the formation of the plies interposing by a rolling action a continuous waterproofing film between a plurality of plies, said waterproofing film being in the form of an emulsion miscible in water at the time it is applied, and drying the sheet thus formed to simultaneously remove the water and cause the waterproofing material to fuse.

LESTER KIRSCHBRAUN.
